UNITED STATES PATENT OFFICE.

GEORGE S. HICE, OF NEW YORK, N. Y., AND JOHN BARNES, OF PHILADELPHIA, PENNSYLVANIA.

SETTABLE-TYPE DEVICE.

1,073,284.

Specification of Letters Patent. Patented Sept. 16, 1913.

Application filed May 10, 1911. Serial No. 626,160.

To all whom it may concern:

Be it known that we, GEORGE S. HICE, residing at the borough of Brooklyn, county of Kings, and city and State of New York, and JOHN BARNES, residing at the city of Philadelphia, Pennsylvania, citizens of the United States, have invented certain new and useful Improvements in Settable-Type Devices, of which the following is a specification.

The improvements relate to settable type devices, and their objects among others are to provide a device which may be placed on the bed or cylinder of a press and secured thereto, and quickly and easily changed to show the commencement, progress and result of a game or other competition from time to time, without removing the device or inserting or removing individual type, and which may be adjusted to suit various conditions and contingencies. It may also be used for other purposes, involving changes in the details of construction, without departing from the spirit of the invention.

The invention consists in the construction, combination and arrangement hereinafter described and claimed and illustrated in the accompanying drawings.

In the said drawings, Figure 1 is a plan of the device secured to a detached portion of the cylinder of a rotary press; Fig. 2 is an end view of the same; Fig. 3 is a side view of the device shown in Fig. 1 with a medial portion cut away to expose the parts behind; Fig. 4 is an enlarged perspective of one of the grooved slugs or slides used with the device; Fig. 5 is an enlarged vertical cross section on the line 5—5 of Fig. 1 looking in the direction indicated by the arrow in that figure; and Fig. 6 is a vertical cross section on the line 6—6 of Fig. 1 looking in the direction indicated by the arrow in that figure.

Many evening newspapers throughout the United States, during the summer months publish on the first page, or prominently on some other page, the scores made by the different prominent baseball teams

inning, and when each edition is printed the 50 scores for the innings that have been reported since the last preceding edition are added until the game is finished, when the totals of the "Runs, hits and errors" are 55 added. This necessitates a great deal of labor and considerable delay, and the methods now in use are such that the work of adding to the score for the printing of each edition is cumbersome, expensive and subject to mistakes. The device which forms 60 the subject matter of this application is designed to overcome these objections.

A represents the shell of a press cylinder, and to this are secured a series of frames B preferably by means of machine screws 65 A¹. Each of these frames B consists of a long horizontal bed plate B¹, and end piece B², a vertical partition B³ of substantially the same proportions and in alinement with the end piece, and a slotted end piece B⁴. 70 The entire frame and its parts are preferably made integral. The slots B⁵ of the part B⁴ are adapted to receive slugs or slides C, which bear the names of the two teams engaged in the match represented by 75 the characters on the frame, and these slugs are held in position detachably by means of longitudinal grooves C¹ near their upper edge on both sides, which receive the rotary latch plate or button D when it is turned so 80 that its greatest length is at right angles to the slugs. This latch is held in position by means of a spring-pressed pin E, which projects normally above the upper surface of the frame B and engages the notch D¹ of 85 the latch plate, and prevents it from disengaging with the slugs. It is held in this position by compression spring E¹ in the body of the frame, and may be depressed by the finger when it is desired to move the 90 plate so as to release the slugs. By this arrangement the slugs may be quickly placed in position or removed therefrom by simply dropping them into the slots or raising them out of the slots and securely held in position 95 while the printing operation is going on.

Mounted on shafts F fixed at their ends in the end piece B² and the partition B³, re-

spectively, are a series of numeral type-wheels G , the first fifteen of which, beginning at the left, have numerals from 1 to 0, and a dash or other suitable character, and 5 the remaining six (arranged in three pairs) numerals G^1 to be used for indicating the total number of runs, hits and errors, respectively. These wheels are rotatably mounted on their shafts and are held against 10 accidental rotation by means of the pawls H mounted on the rods J and normally pressed into the notches G^2 by the plate spring I mounted on the frame. As the 15 notches and pawl points are conical the wheels may be moved in either direction.

Beneath each pair of baseball scores it is customary to print the batteries and umpire, and in order to provide for this, and such other information as may be desired, a 20 space is left between each score frame and the next lower frame for the reception of a linotype slug N bearing such information. A latch or clamp K adapted to engage one edge of this slug is mounted near the end 25 of each frame B , and is normally held in its engaging position by the spring K^1 pressing against its extension K^2 . The pointed end of the latch K will "bite" into the soft metal of which the slug is composed and the 30 slug will be held at its opposite end by the projecting lugs B^6 on the end of the end piece B^2 , between which end piece and the opposite end piece M the score frames are positioned.

35 By the use of this device the names of the two competing teams may be set in the proper position, and the score for each inning added for the different editions, until the game is finished, and the totals of runs, 40 hits, and errors then added, all without taking the form or any part thereof off the cylinder, and by simply rotating the numeral wheels until the desired numeral is uppermost. The wheels are, of course, provided 45 with blanks so that the innings to be played will not display any numeral or other mark, and the dashes on the wheels may be used to fill up the spaces representing innings not played, if desired. The frames B carrying the type numeral wheels G , with their pawls and springs, and the latches K will 50 remain fixed to the cylinder, and in order to start a score it is only necessary to put in the slides bearing the names of the teams, and, if desired, the slug bearing the names 55 of the batteries and any other information either above or below the score.

It will be understood that the usefulness 60 of this device is not confined to base-ball scores and that it may be used for various analogous purposes. It has been described, however, in connection with its use for the purpose of setting up such scores for the

reason that this is its primary purpose and 65 serves to illustrate the operation of the device.

What we claim is:—

1. A device of the character described comprising a frame, wheels bearing type characters rotatably mounted in a plurality 70 of parallel rows, means for retaining each wheel against accidental rotation at positions corresponding with the characters thereon, said frame having recesses corresponding in number to the rows of wheels 75 and adjacent to the same, slugs or slides bearing type adapted to be placed in said recesses, a latch mounted on said frame adjacent to one of said recesses adapted to project over the same when in one position and 80 means for holding the said latch in that position.

2. A device of the character described comprising a frame, wheels bearing type characters rotatably mounted in a plurality 85 of parallel rows, means for retaining each wheel against accidental rotation at positions corresponding with the characters thereon, said frame having recesses corresponding in number to the rows of wheels 90 and adjacent to the same, slugs or slides bearing type adapted to be placed in said recesses, and a latch mounted on said frame adjacent to a plurality of the said recesses and adapted to project over the same when 95 in one position.

3. A device of the character described comprising a frame, wheels bearing type characters rotatably mounted in a plurality 100 of parallel rows, means for retaining each wheel against accidental rotation at positions corresponding with the characters thereon, said frame having recesses corresponding in number to the rows of wheels 105 and adjacent to the same, slugs or slides bearing type adapted to be placed in said recesses and provided with a longitudinal 110 groove, and means for engaging in said groove.

4. A device of the character described 110 comprising a frame, wheels bearing type characters rotatably mounted in a plurality of parallel rows, means for retaining each wheel against accidental rotation at positions corresponding with the characters 115 thereon, a slug bearing type adapted to be positioned adjacent to one of said rows and parallel therewith, and means for detachably holding the same in position, comprising a spring-pressed tooth adapted to engage the slug.

5. A device of the character described comprising a frame, wheels bearing type characters rotatably mounted in a plurality 125 of parallel rows, means for retaining each wheel against accidental rotation at posi-

tions corresponding with the characters thereon, a slug bearing type adapted to be positioned adjacent to one of said rows and parallel therewith, and means for detachably holding the same in position comprising a spring-pressed tooth of metal harder than the metal of the slug adapted to engage and make an indentation in the same.

In testimony whereof we have affixed our signatures in presence of two witnesses.

GEORGE S. HICE.
JOHN BARNES.
